(57) **CLAIM**

The ornamental design for a towel dispenser, substantially as shown and described.

DESCRIPTION

FIG. 1 is a front, raised perspective view of a towel dispenser according to the invention;

FIG. 2 is a front view of the towel dispenser of FIG. 1;

FIG. 3 is a rear view of the towel dispenser of FIG. 1;

FIG. 4 is a right side view of the towel dispenser of FIG. 1;

FIG. 5 is a left side view of the towel dispenser of FIG. 1;

FIG. 6 is a top view of the towel dispenser of FIG. 1;

FIG. 7 is a bottom view of the towel dispenser of FIG. 1; and,

FIG. 8 is a front, lowered perspective view of the towel dispenser of FIG. 1.

The broken-lines shown on the surface of the drawings show portions of the towel dispenser that form no part of the claimed design.

1 Claim, 7 Drawing Sheets
